UNITED STATES PATENT OFFICE

JOHN E. SCHEUERLEIN, OF BAY CITY, MICHIGAN

DEVICE AND METHOD FOR TIGHTENING WIRE

Application filed January 23, 1933. Serial No. 653,039.

This invention relates to a device and method for tightening loose wires on all kinds of wire fences, telephone and electric lines, brace wires, as well as wires used for repairing and wiring together the broken parts of various tools and mechanical devices.

One of the prime objects of the invention is to design a tool for tightening and taking up the slack wire on fences and the like, so that a tight wire may be had.

Another object is to provide an adjustable tool for taking up the slack in a wire which is secured to spaced apart supports, so that the strand may be tightened and held tight.

A further object is to provide a very simple, practical, and economical tool which can be readily manufactured and assembled, which is composed of few parts all of rugged construction, and which can be readily operated by unskilled workmen.

A further object still is to provide a device of rugged construction which requires little or no repair, which is efficient in operation, and which is of a size to permit it being readily handled and operated.

With the above and other objects in view, the present invention consists in the combination and arrangement of parts, herein-after more fully described, illustrated in the accompanying drawing, and particularly pointed out in the appended claims, it being understood that changes may be made in the form, size, proportion, and minor details of construction, without departing from the spirit, or sacrificing any of the advantages of the invention.

In the drawing—

Fig. 1 is a view of my improved wire tightening device.

Fig. 2 is a fragmentary part sectional view showing the method of securing the swivel end to the standard.

Fig. 3 is an enlarged detail plan view of the yoke.

Fig. 4 is an end view thereof.

Fig. 5 is a view similar to Fig. 1, showing the device in position for tightening a loose strand of wire.

Fig. 6 is also a similar view, illustrating

the tightening operation partly completed.

Fig. 7 is a view similar to Fig. 6 showing the tightening operation completed.

Fig. 8 is a view showing the wire tightened and the device removed and the taut sections secured together.

Fig. 9 is a view showing the loose section cut away.

Referring now more particularly to the drawing in which I have shown the preferred embodiment of my invention, the tool comprises a tubular threaded screw rod member 5, the upper end section of which is shouldered as shown at 6, said end section being bored to receive a transversely disposed handle member 7 as usual. A yoke member 8 is mounted on the screw rod 5, and is formed as clearly shown in Figs. 3 and 4 of the drawing, a vertically disposed threaded opening 9 being provided in said yoke, the ends being grooved as shown at 10, the inner end of the grooves being rounded as shown at 11, so that sharp corners are eliminated.

A swivel member 12 is secured in the lower end of the screw rod member 5, and a pilot 13 is formed integral therewith, said pilot projecting into a suitable recess provided in the end of the member 5, the lower end of the swivel being grooved as at 14, and the edges are rounded as at 15 to eliminate any sharp corners.

Fence wires are stretched by persons climbing over them, by cattle and animals endeavoring to get through, and by the sagging of the supports to which the wire strands are secured, and when it is desired to tighten a loose strand or wire which is indicated at 16, I provide an additional short length 17, which I place over the yoke member 8 with the ends of the wire leading down and over the grooved portions 10. These ends are wrapped around the strand 16 in spaced apart relation as shown at 18, and the swivel end of the tool is placed over the strand 16, all as shown in Fig. 5 of the drawing.

The operator then grasps the handle 7, revolving said handle to thread the screw rod through the yoke member 8, forcing the

central portion "A" of the wire 16 outwardly as shown in Fig. 6, the bend "B" in the wire preventing the wrapped section 18 from slippage on the strand 16. Continued 5 rotation of the handle 7 forces the center section "A" outwardly to position as shown in Fig. 7, so that the wrapped sections 18 draw the end sections of the wire 16 toward each other. When the wire has been drawn 10 as taut as possible, I take another strand of wire 19 and securely wrap or twist the ends to the main strand 16 at the point 20, and I then remove the tool and cut the wire sections 17 with a pair of conventional pliers 15 or other tool, so that the appearance of the completed structure is as shown in Fig. 9 of the drawing.

The operation is simple and can be readily performed by inexperienced labor. It 20 merely requires the addition of the short lengths of wire 17 and 19, and the strands of the wire which make up the fence can be readily tightened, so that old loose wire is made taut and serves exactly the same purpose 25 as new tightly stretched wire.

I wish to direct particular attention to the fact that the opening 9 in the yoke is offset with the relation to the grooves in the ends thereof, so that there will be no interference or obstruction when the wires 17 30 and 19 are applied.

The device is adaptable for many purposes, in fact anywhere that wire is used, and while in the present instance I have 35 shown the device as used for tightening and stretching slack fence wire, it will be readily understood this is but one of the uses to which it may be put.

From the foregoing description it will 40 be obvious that I have perfected a very simple, practical, rugged, and efficient device and method for tightening loose strands of wire which are secured to spaced apart supports.

45 What I claim is:

1. A wire tightening tool of the class described and comprising a threaded screw rod provided with a handle on the one end thereof, a grooved swivel member secured 50 to the opposite end, and an offset yoke member adjustably mounted on said screw rod and provided with rounded grooves in the ends thereof.

2. A wire tightening tool of the class described and comprising a threaded screw

rod provided with a handle on the upper end thereof, a grooved swivel member secured to the opposite end of said screw rod and adapted to engage the wire to be tightened, a transversely disposed yoke adjustably mounted on the screw rod and provided with grooved and rounded ends, and a wire placed over said yoke and groove and adapted to be secured to the main wire, so that the handle can be manipulated to draw the end sections of the main wire towards each other. 70 75

3. A wire tightening tool of the class described, and comprising a screw rod provided with a transversely disposed handle on one end thereof, a swivel member secured to the opposite end and provided with a groove in the bottom face thereof, an offset yoke member adjustably mounted on the screw rod, and grooves in the ends of the yoke member, said grooves being disposed to accommodate a strip of wire without obstruction from the screw rod. 80 85

4. The method of tightening a wire which consists in attaching both ends of a separate strand of wire to the main strand at spaced apart points intermediate its length, forcing the intermediate section outwardly from the main strand to pull the end sections of the main strand towards each other, and then securing the taut sections securely together. 90 95

5. The method of tightening a main wire which consists in attaching the ends of a separate section of wire to the main section 100 at a point intermediate its length, then forcing the section of the main wire between the attached ends outwardly from the main wire to draw the end sections of the main wire taut, and then wiring across the bent 105 section to secure the end sections rigidly together.

6. The method of tightening a main wire which is secured to spaced apart supports, which consists in attaching both ends of a separate strand of wire to the main wire at a point intermediate its length, bending the section between the attached ends outwardly from the main wire to draw the end sections of the main wire towards each other, and then attaching a separate strand to secure the end sections together. 110 115 120
